ATTORNEY.

UNITED STATES PATENT OFFICE.

LEO F. FAY, OF ECORSE, MICHIGAN.

WASHING-MACHINE.

1,390,521.

Specification of Letters Patent. Patented Sept. 13, 1921.

Application filed February 7, 1921. Serial No. 442,980.

To all whom it may concern:

Be it known that I, LEO F. FAY, a citizen of the United States, residing at Ecorse, county of Wayne, State of Michigan, have 5 invented a certain new and useful Improvement in Washing-Machines, and declare the following to be a full, clear, and exact description of the same, such as will enable others skilled in the art to which it pertains 10 to make and use the same, reference being had to the accompanying drawings, which form a part of this specification.

This invention relates to an improvement in washing machines shown in the accompanying drawings and more particularly described in the following specification and claims.

The primary object of the invention is an improvement in the construction of the 20 washing machine shown and described in my co-pending application for patent filed February 9, 1920, Serial Number 357,219.

The present invention relates more particularly to a yieldable driving connection 25 established between the electric motor and the vertical reciprocating spindle carrying the vacuum cup or beater,—in which a rocking lever having an automatic laterally movable fulcrum is provided whereby in the 30 event of overloading the motor, the latter will not be stalled but continue to operate that it may not be injured or burned as a result of the "overload."

With the foregoing and other objects in 35 view which will appear as the description proceeds, the invention further resides in the combination and arrangement of parts and in the details of construction herein-after described and claimed, it being understood 40 that changes may be made in the precise embodiment of the invention herein shown without departing from the spirit of the same.

In the accompanying drawings forming 45 part of this specification:

Figure 1 is a vertical cross-sectional view through the clothes container or tub of a washing machine, showing an electric motor, the vertically reciprocable spindle 50 carrying the beater, the automatic laterally movable rocking lever and connecting mechanism for actuating said spindle by the motor.

Fig. 2 is an enlarged detail view with 55 parts in section of a pair of co-acting clevises—to which the rocking lever for actuat-

ing the beater spindle is fulcrumed;—taken on or about line 2—2 of Fig. 1.

Fig. 3 is an elevation of a detail partly in section of the link connection between 60 the rocking lever and the reciprocating spindle;—taken on or about line 3—3 of Fig. 1.

It is well known that if as a result of carelessness the volume or character of the 65 clothes placed in a washing machine actuated by an electric motor should prevent the "beater" from reciprocating it would cause the motor to "stall" and would probably eventuate in "burning out" the latter, 70 at great loss and inconvenience to the owner.

The purpose of this invention therefore is to provide means whereby in the event of the tub being packed with clothes the operation of the motor will not cease even though 75 the beater is held against moving the length of its predetermined stroke.

Referring now to the letters of reference placed upon the drawings:

A, denotes a clothes container or tub 80 mounted on a suitable supporting frame B. A' indicates a removable cover for the tub. C, designates an annular beater secured to the upper end of a vertically movable spindle D reciprocable through an elongated 85 sleeve E mounted in the tub A, and which is fitted with the usual stuffing box, not shown.

F is a link pivoted to the end of the spindle D and to the end of a rocking lever G, in turn fulcrumed at G' to a pair of clevises 90 H and H'. The clevis H is pivoted to a bracket I, forming part of the leg extension J, bolted to one of the legs J^a of the frame.

The clevis H' is attached to an adjustable eyebolt to which is connected a spring L 95 secured to a depending bracket L^a, attached to the supporting frame of the machine.

M is a spring attached at one end to the frame and at the other to a link F, connecting the rocking lever G with the spindle E 100 of the beater. N is an electric motor. N' is a shaft actuated by the motor provided with a worm gear (not shown) in mesh with a worm gear (not shown) on the crank shaft P,—journalled in a suitable bracket P', depending from the frame of the machine.

Q indicates a pitman connecting the crank shaft P with the rocking lever G.

Having now indicated the several parts by reference letters the construction and operation of the device will be readily understood.

It may be assumed that a sufficient over-load of clothing has been placed in the tub to arrest the proper operation of the beater. This however will not cause the motor to 5 stall or "burn-out" as the crank shaft P continuing its counter clockwise operation will force the rocking lever G,—and the clevises to which it is fulcrumed to the position indicated in dotted lines in Fig. 1, against the 10 action of the spring L. Upon the crank shaft passing the point indicated in dotted lines in its counter clockwise movement the spring L will return the clevises and rocking lever to their normal position, the spring 15 M, serving to check the back-lash or jar that would otherwise result. The leg extension J being a relatively heavy casting, serves as a stop or abutment to receive the end of the rocking lever and the spring M 20 has sufficient tension to relieve the jar that would otherwise result from the return of the rocking lever to its normal position.

In the ordinary operation of the machine the clevises H and H' will not be moved 25 laterally to change the position of the fulcrum of the rocking lever;—this action only taking place when the volume of clothes placed in the tub is above normal or when the motor is forced to stop from some other 30 abnormal cause, as when the spindle is held against reciprocation while the motor is in operation.

Having thus described my invention what I claim is:

- 35 1. A motor, a movable spindle fitted with an operated device, a rocking lever, means actuated by the motor for operating the rocking lever, a movable fulcrum for the rocking lever whereby the rocking lever may 40 be automatically shifted to adjust itself to load conditions, means for returning and normally retaining the movable fulcrum in its normal position, whereby the rocking lever may operate under normal load conditions, a link connection between the swinging 45 end of the rocking lever and the spindle, and resilient means for checking the sudden return of the rocking lever to its initial position.
- 50 2. A motor, a vertically movable spindle, an operated device fitted to the spindle, a rocking lever, means actuated by the motor for operating the rocking lever, an adjustable fulcrum for said rocking lever, resilient 55 means for returning and yieldingly maintaining said lever in its normal operative position, a link connection between the swinging end of the rocking lever and the

spindle, and resilient means for checking the jar due to the sudden return of said 60 rocking lever to its normal position.

3. A motor, a vertically movable spindle, an operated device fitted to the spindle, a rocking lever, means actuated by the motor for operating the rocking lever, an adjustable fulcrum for said rocking lever, resilient 65 means for returning and yieldingly maintaining said lever in its normal operative position, a link connection between the swinging end of the rocking lever and the spindle, resilient means for checking the jar due to the sudden return of said rocking lever to its normal position, and a suitable abutment bolted to the end of the frame, adapted to receive the impact of the rocking lever when restored to its normal position 70 through the action of the first named resilient means.

4. A motor, a vertically movable spindle, an operated device fitted to the upper end 80 of the spindle, a rocking lever, a clevis pivotally connected with the frame, a second clevis pivoted to the first named clevis and to the end of the rocking lever to provide an adjustable fulcrum for said lever, a 85 spring connected with the frame and with said last named clevis to yieldingly maintain the rocking lever and fulcrum in its normal position, a link connection between the swinging end of the rocking lever and the spindle, a spring connected with said link connection and the frame to check the sudden jar occasioned through the return of the rocking lever to its normal position under the action of the first named spring, 90 and means actuated by the motor for operating the rocking lever.

5. In a washing machine, a motor, a movable spindle fitted with a clothes beater, a rocking lever, means actuated by the motor 100 for operating the rocking lever, a movable fulcrum for the rocking lever whereby the rocking lever may be automatically shifted to adjust itself to load conditions, a link connection between the swinging end of the 105 rocking lever and the spindle, and means for returning and normally maintaining the movable fulcrum in its initial position, whereby the rocking lever may actuate the clothes beater under normal load conditions. 110

In testimony whereof, I sign this specification in the presence of two witnesses.

LEO F. FAY.
